(57) **CLAIM**

The ornamental design for footwear, as shown and described.

DESCRIPTION

FIG. 1 is a front right perspective view of footwear showing my new design;

FIG. 2 is a top view of the design shown in FIG. 1;

FIG. 3 is a left side view of the design shown in FIG. 1;

FIG. 4 is a right side view of the design shown in FIG. 1;

FIG. 5 is a front view of the design shown in FIG. 1; and,

FIG. 6 is a rear view of the design shown in FIG. 1.

The bottom of the footwear forms no part of the claimed design. The dash-dot-dash lines on the bottom illustrate an unclaimed boundary line that forms no part of the claimed design. The thin evenly spaced broken lines on the upper illustrate a stitching that forms no part of the claimed design. The bold evenly spaced broken lines on the top of the midsole illustrate a stitching that forms no part of the claimed design. The uneven broken lines illustrate laces that form no part of the claimed design.
